Filed Oct. 29, 1969, Ser. No. 19,831

Term of patent 14 years

Int. Cl. D23—01

U.S. Cl. D23—10

FIG. 1

FIG. 5

FIG. 2

FIG. 3

FIG. 6

FIG. 4

FIG. 1 is a top plan view of a root feeder showing my new design;

FIG. 2 is a front elevational view thereof;

FIG. 3 is a bottom plan view thereof;

FIG. 4 is a rear elevational view thereof;

FIG. 5 is an elevational view taken from one end thereof; and

FIG. 6 is an elevational view taken from the end opposite that shown in FIG. 5.

For convenience of illustration, the tubular upright feeder stem is broken away in FIGS. 2, 4, 5 and 6 to indicate indeterminate length.

I claim:

The ornamental design for a root feeder, substantially as shown and described.
